[57] CLAIM

The ornamental design for a bumper guard for push
bars, as shown and described.

DESCRIPTION

FIG. 1 is a left front perspective view of a bumper
guard for push bars, showing my new design, it being
understood that the broken lines are for illustrative
purposes only and form no part of the claimed design;
FIG. 2 is an enlarged left side elevational view thereof,
the right side being a mirror image of that shown;
FIG. 3 is a front elevational view of FIG. 2;
FIG. 4 is a rear elevational view of FIG. 2; and
FIG. 5 is a bottom plan view of FIG. 2, the top being
identical thereto.

FIG. 1

FIG. 2

FIG. 3

FIG. 4

FIG. 5
